Inventor
Edgar L. York
Atty.

Patented Nov. 11, 1924.

UNITED STATES PATENT OFFICE.

EDGAR L. YORK, OF PEORIA, ILLINOIS.

IRONING MACHINE.

Application filed May 9, 1921. Serial No. 468,033.

To all whom it may concern:

Be it known that I, EDGAR L. YORK, a citizen of the United States, and a resident of Peoria, in the county of Peoria and State of Illinois, have invented certain new and useful Improvements in Ironing Machines, of which the following is a full, clear, and exact description, reference being had to the accompanying drawings, forming part of this specification.

My invention relates to ironing machines particularly adapted for household work in ironing clothes and other materials and in which the material to be ironed is fed between the platen which is heated and a plurality of feed rollers which, in addition to carrying the material through the machine, press it against the platen.

One object of my invention is to provide the machine with means for applying pressure to the platen whereby the material will receive a greater amount of pressure as it leaves the machine than it receives as it enters.

Another object of my invention is the provision of means whereby the platen may be readily removed from the machine for cleaning or other purposes, and as easily re-inserted for use.

Another object of my invention is to construct and organize the machine in such a manner that the platen may be yieldingly pressed against the feed rollers and, at the will of the operator, moved away from the feed rollers, and further that as the platen is moved away from the feed rollers, the edge of the platen which is nearest the operator and below the entering feed roller, will move away from the feed roller before the platen leaves the other roller.

Other objects of my invention will be described in the specification.

The novelty of my invention will be hereinafter more fully set forth and specifically pointed out in the claims.

In the accompanying drawings:

Fig. 1, Sheet 1, is an end elevation of a machine embodying my invention.

Fig. 2, Sheet 1, is an enlarged rear view of the upper right portion of the machine.

Fig. 3, Sheet 2, is a detail view partly in section of the means for mounting and moving the platen.

Fig. 4, Sheet 2, is a plan view of a portion of the foot pedal mechanism and its

latch, for moving and holding the platen away from the feed rollers.

The same numerals of reference are used to indicate identical parts in all the figures.

As illustrating one form of machine embodying my invention, I have shown a structure comprising a frame consisting of end members 1 secured together by cross members 2 and carrying a feed board 3 and discharge board 4, the frame 1 preferably being provided with castors 5 so that the machine can easily be moved about from place to place.

Two cushioned feed rollers 6 and 7 are mounted as by bearings 8, Fig. 2, upon the end members 1, the feed roll 6 being driven by a gear 9 which, together with the other gearing is shown in dotted lines in Figs. 1 and 2, the feed roller 7 being provided with a gear 10, both of these gears meshing with and being driven by a gear 11 which is secured to and driven by worm wheel 12, the latter being driven by worm 13 which in turn is driven by a sheave 14 from which a belt 15 extends to a suitable sheave on the motor 16, the latter being carried on the bracket 17 which in turn is carried by one of the end members 1 of the machine.

A suitable belt guard 18 covers the sheave 14 and the belt 15 as well as the sheave 18 on the motor.

The gearing previously described is enclosed in a housing 19 which is preferably made so that it retains lubricant as well as prevents injury to the operator.

A member or bell crank 20 is carried by each end member 1 and is provided with a boss or trunnion 21 which is adapted to engage a socket or saddle 22 projecting from the adjacent end of the platen 23 which, as clearly shown in Fig. 3, is mounted to an angle to a horizontal plane, its receiving or entering edge being at the greatest elevation so that the material in passing through the machine travels downwardly away from the operator, who stands to the left of Fig. 1, this being the front of the machine. The bell crank 20 is pivotally mounted as at 24 to the end member 1 and as this bell crank is rocked on its pivot, the platen 23 moves 100 toward or from the rollers 6 and 7, depending on which way the bell crank 20 is moved. The free end of the bell crank 20 is provided with an eye 25 through which a rod 26 passes, the rod being provided with 110

adjusting nuts 27 so that the position of the parts may be properly set.

- The lower end of each rod 26 is connected to an eye 28 at the upper portion of a lever 29, one of these levers being adjacent each of the end members 1, the levers 29 being carried by a square shaft 30, Fig. 4, which is pivotally mounted as at 31 on the end members 1 the lower ends of the two levers 29 being connected together by a tube 32 which together with the levers forms a pedal across the front of the machine, the construction of the parts just described being such that when the operator desires to move the platen away from rollers 6 and 7, the levers 29 are moved around the pivotal point 31 by pressing the foot on the tube 32 and thus moving the bell crank 20 and the platen 23.
- 20 A compression spring 33 surrounds the upper portion of a rod 26 and bears against the eye 25 of the bell crank 20 at its upper end and against a movable abutment 34 at its lower end, the spring exerting its pressure to raise the bell crank 20 and the platen 23 to press the latter against the rollers 6 and 7. The abutment 34 is pivoted to the end member 1 as at 35 and is provided with an adjusting screw 36 by means of which it may be rocked on its pivot to increase or decrease the pressure produced by the spring 33.

It is to be noted that the point of connection between the platen 23 and the bell crank 20 is located between the points of contact between platen and rollers 6 and 7 though somewhat closer to the roller 7 than to the roller 6 so that a greater amount of pressure applied by the spring 33 is against the roller 7 and it is also to be noted that the platen is counter-weighted as at 37, Fig. 3, so that its forward or upper edge moves downward before the rear edge moves when the bell cranks 20 are pulled downward by the foot pedal.

- When it is desired to move the platen downward from the rollers 6 and 7 and to hold it in its lowered position as shown by the dotted lines 38 of Fig. 3, the pedal 32, 50 is moved toward the rear of the machine until a lug 39 carried by the lever 29 engages latch 40 carried by the end member 1, this latch being shown more clearly in Fig. 4, it being provided with a vertically arranged portion 41 which extends to a position where it may be readily engaged by the shoe of the operator to the end that it may be released when desired. The latch 40 is held in operating position by a spring 42 and is restrained from moving too great a distance by a finger 43 which bears against the web of the member 1 as clearly shown in Fig. 4, the latch being pivotally mounted as by a bolt 44.

65 The operation of the machine is as fol-

lows: When it is desired to pass material through the machine, the burner 45 which is carried by the platen, and which ordinarily is fitted for burning gas though electricity or any other suitable heating medium 70 may be employed, is set in operation to heat the platen, the platen meanwhile being held in its lowered position through the medium of the latch 40 in which position the platen is steadied by pins 46, shown in section in Fig. 3, which project inwardly from the end member 1, whereupon when the platen has been sufficiently heated, and the operator has placed the material to be ironed either upon the feed board 3 or, if the pieces are large, such as sheets, tablecloths, etc., in the pocket or receptacle 47 of the discharge board 4, and the motor 16 started to cause the rotation of the roller 6-7, the operator releases the latch 40 and permits the spring 33 to raise the platen into contact with the roller 6-7 and feeds the material into the machine until it is engaged by the roller 6, from which it passes to the roller 7 and so through the machine. Should it be desirable or necessary to permit the work to enter a certain distance and then release it, this may be accomplished by pressing the pedal 32 which, through the connections previously described lowers the platen whereupon the position of the work may be shifted, or it may be retracted as desired and the platen again be permitted to contact with the rollers and the work continued.

It is to be observed that the platen, when it is lowered, leaves the roller 6 before it leaves the roller 7 due to the counterweight 37 previously described, to the end that should it be necessary to only slightly release the work for the purpose of straightening it, a slight amount of movement of the pedal will result in releasing the pressure of the platen and will lower the entering edge thereof slightly. Should the work be of such a nature that it cannot readily be fed into the machine when the platen is in full contact with the rollers, the entering edge of the platen may be lowered as previously described to permit the work to be easily introduced.

It is to be noted that the point of application of the upward pressure to the platen from the bell cranks 20 is out of center between the contact points of rollers 6 and 7 and is closer to the roller 7 than to the roller 6 to the end that a greater pressure will be applied to the roller 7 for the finishing operation of the ironing, the contact of the material with the platen produced by the roller 6 being primarily for the purpose of thoroughly drying the material.

When it is desired to remove the platen from the machine, this may be accomplished by simply latching the pedal back to lower

the platen as previously described, whereupon the platen may be lifted from its engagement with the trunnions 21 of the bell cranks 20 and moved rearward and downward out of the machine, whereupon the platen may be cleaned if required or polished, etc, and again reinserted in the machine and engaged with the trunnions of the bell cranks 20, and the pedal unlatched if desired as previously described.

The feed rollers 6 and 7 are preferably constructed of a core or tube upon which a considerable thickness of suitable cloth or other yielding material is placed so that the rollers when completed are yielding to a limited extent, to the end that when the platen is in operating position a sufficient surface contact is obtained between the platen and the rollers to properly feed the material through the machine.

Having thus fully described my invention, I claim:

1. In an ironing machine the combination of a plurality of cushioned work feeding rolls, driving mechanism therefor, a platen below the rolls, means for heating the platen, spring operated means for pressing the platen against the feed rolls, foot operated means for overcoming the latter means to lower the platen, a latch cooperating with the foot operated means to hold the platen in lowered position, and disengageable connections between the spring operated means and the platen whereby the latter may be removed from the machine.

2. In an ironing machine the combination of a pair of cushioned work feeding rollers, a platen co-operating with the rollers, means for heating the platen, spring operated means for pressing the platen against the rollers, means for moving the platen away from the rollers, and a rocking connection between the platen and the spring operated pressing means located between the lines of contact of the platen and the rollers and out of center between these lines of contact whereby greater pressure will be applied to one roller than to the other.

3. In an ironing machine the combination of an entering cushioned work feeding roller, a second cushioned work feeding roller mounted below and to the rear of the first mentioned roller, a platen co-operating with both rollers, means for heating the platen, spring operated means for pressing the platen against the rollers, means for moving the platen away from the rollers, a rocking connection between the platen and the spring operated pressing means located between the lines of contact of the rollers with the platen and closer to the second feed roller whereby greater pressure will be applied to the second feed roller than to the entering feed roller, and means for causing the platen to move away from the entering feed roller before it leaves the second feed roller when the means for moving the platen away from the rollers is operated.

EDGAR L. YORK.
